UNITED STATES PATENT OFFICE.

ROBERT J. MCKAY, OF PITTSBURGH, PENNSYLVANIA.

STAY-BOLT.

1,308,185.

Specification of Letters Patent.

Patented July 1, 1919.

Application filed May 5, 1915. Serial No. 26,130.

To all whom it may concern:

Be it known that I, ROBERT J. MCKAY, a citizen of the United States, and resident of Pittsburgh, in the county of Allegheny and State of Pennsylvania, have invented 5 a new and useful Improvement in Stay-Bolts; and I do hereby declare the following to be a full, clear, and exact description thereof.

10 My invention relates to stay-bolts. The invention has relation more particularly to stay-bolts for uniting boiler-plates, such as the outside shell and fire-box shell of locomotives, and to the type described and 15 claimed in Letters Patent of the United States No. 792,863, of June 20, 1905, to George S. Thompson, the distinctive features of which being that the eye-head and eye-bolt are interlinked by their eye-loops, 20 so as to give a certain amount of play, while at the same time independent rotary movement of the parts is prevented.

The present invention consists, generally 25 stated, in a stay-bolt with a shank portion having an eye-loop formed at one end thereof, the eye-head comprising an eye-loop portion having an eye-loop engaging the eye-loop of the shank, and a longitudinally divided threaded tail portion engaged by a 30 cap or hollow nut which completes the eye-head.

In the accompanying drawing, Figure 1 35 is a view of my improved stay-bolt partly broken away; Fig. 2 is a longitudinal section; Fig. 3 is a view of the eye-loop portion of the eye-head; and Fig. 4 is a view of the manner in which the eye-loop portion of the eye-head is inserted in the eye-loop of the shank.

40 The numeral 2 designates the shank or bolt-portion which is provided with the loop 3 at one end and the threaded portion 4 at the opposite end.

The eye-head 5 is made up of two parts, 45 namely, the eye-loop portion 6 and the cap or hollow-nut 7. The eye-loop portion 6 is first formed in substantially the shape shown in Fig. 3 with the semi-circular diverging tail-pieces 8 having the threads 9 formed 50 thereon. To connect the eye-loop portion 6 up with the eye-loop 3 of the shank 2, one of the tail-portions 8 is inserted in the opening of the eye-loop 3 at right angles to the axial line of the shank, whereupon the 55 eye-loop portion 6 is turned around to the

position indicated in dotted lines Fig. 2. Pressure is then applied to the tail-portions 8 of the eye-bolt portion 6 to force said tail-portions into contact, as indicated in Fig. 2. It should be mentioned that the eye-loop 60 portion 6 is heated sufficiently to permit of this pressing of the tail-portions 8 into contact so that the cap 7 with the internal threads 10 may be screwed onto the threaded portion 9 of the tail-portion 8. The 65 threads 10 form projections on the tail piece, and any kind of a projection other than threads might be employed to form an interlocking connection between the cap and the tail piece. 70

The closing of the tail-portions 8 of the eye-loop portion 6 in the manner above described, closes up the opening 11 of the eye-loop portion 6, so that said opening conforms practically to the cross section of the 75 eye-loop 3 of the shank 2 taken along the line a—a, Fig. 4.

To bring the tail-pieces 8 of the eye-loop portion 6 into contact, the eye-loop portion 6 is not heated to a welding heat and consequently the opening 11 can be made to fit quite accurately the eye-loop 3 at a—a, so that there is practically no longitudinal movement between the shank 2 and the eye-head, but at the same time there is no binding 80 so as to interfere with the play at this point between the eye-head and the shank. Both the eye-head and the shank are free to move laterally and perpendicularly, the one with relation to the other, so as to take 85 care of the uneven expansion and contraction between the boiler sheets, and so relieve the strain. As stated above, when the axial line of the eye-head and the shank are in alinement, there is practically no longitudinal movement, the one with reference to the other, due to the close fit of the opening 11 in the eye-head and the eye-loop of the shank at a—a, but this opening being larger 90 than the links of the eye-loop 3 at opposite 95 sides of the line a—a, sufficient clearance is given to allow for the free lateral movement 100 of the eye-head or shank with reference to each other.

The eye-loop portion 6 of the eye-head 105 has the lugs 12 formed thereon, which form bearing points giving freer movement than would be permitted were the eye-loop portion to fit snugly within the opening loop of the shank. 110

The cap 7 is provided with the wrench-seat 13 for screwing the stay-bolt into position.

By my invention I form my stay-bolt 5 without the necessity of welding any of the parts, which welding sometimes acts to distort the parts in such a way as to cause them to bind, but by simply forcing the shank portions 8 into contact and then applying 10 the cap 7, I get a very strong construction without resorting to welding.

What I claim is:

1. A stay-bolt comprising a shank having a loop, an eye-head having an eye-loop engaging the loop of said shank, said eye-head comprising an eye-loop portion formed with a longitudinally divided tail-piece, and a cap inclosing said tail-piece.

2. A stay-bolt comprising a shank having a loop, an eye-head having a loop engaging the loop of said shank, said eye-head consisting of an eye-loop portion formed with a longitudinally-divided tail-

piece, a projection on said tail-piece, and a cap inclosing said tail-piece and forming 25 an inter-locking connection with said projection.

3. A stay-bolt comprising a shank having a loop, an eye-head having a loop engaging the loop of said shank, said eye-head 30 consisting of an eye-loop portion having a longitudinally divided tail-piece having threads thereon, and an externally threaded cap engaging the threads of said tail-piece.

4. A stay-bolt comprising a shank having a loop, an eye-head having a loop engaging the loop of said shank, and the eye-loop portion of said head having guide-lugs thereon adapted to engage the inner faces of the loop of said shank.

In testimony whereof I, the said ROBERT J. MCKAY, have hereunto set my hand.

ROBERT J. MCKAY.
